DRINKING VESSEL

Jack H. Rosen, Pittsburgh, Pa.

Application February 15, 1935, Serial No. 6,727

7 Claims. (Cl. 62—91.5)

This invention relates to drinking or dispensing vessels such as drinking glasses, mugs, steins, pitchers, in which it is desired to maintain the liquid in the vessel at a relatively low temperature.

One object of my invention is to provide a vessel having two compartments whereby the liquid to be cooled may be kept in one compartment and cooling medium kept in the other compartment and out of contact with liquid to be cooled.

Another object of my invention is to provide a vessel of the foregoing character having two compartments separated by a partition, with means for cooling the entire surface of the partition between the two compartments thereby to ensure maximum cooling efficiency of the vessel.

One particular object of my invention is to provide a modified beer mug for serving beer, in which a small compartment is provided centrally within the usual liquid containing compartment of the mug in order that the beer surrounding the auxiliary central compartment may be kept cold for a relatively long time by means of a cooling medium within the central compartment.

Another object of my invention is to provide a drinking or dispensing vessel embodying the principle of construction of the beer mug just referred to, in which a small piece of carbon dioxide may be utilized as the cooling medium to permit the use of a relatively small auxiliary cooling compartment within the main compartment, with provisions for ready access to the cooling compartment for insertion of the cooling medium and for easy cleaning of the auxiliary compartment.

In order to provide for cooling of a liquid in a serving glass or dispenser without immersing a cooling medium in direct contact with the liquid to be served or dispensed, I provide an auxiliary shell to extend into the liquid containing compartment and so constructed that the wall of the shell, which serves as a partition between the liquid containing compartment and the space or compartment contained within the auxiliary shell. The space within the auxiliary shell is then supplied with the cooling medium by means of which the heat from the liquid in the main compartment is conducted away.

The vessel I have provided is particularly adapted for use with dry ice or solid carbon

dioxide, as the cooling medium. In order to obtain the maximum efficiency of the cooling medium, the carbon dioxide gas is caused to engage and pass along the inner surface of the wall of the auxiliary vessel, which serves as the cooling partition between the cooling compartment and the main compartment.

One embodiment of my invention consisting of a drinking glass such as ordinarily used for beer, is illustrated in the accompanying drawing in 10

Figure 1 is a side elevational view of a drinking glass to which the invention is applied;

Figure 2 is a vertical side view partly in elevation and partly in section with parts broken away to show the disposition of the cooling chamber within and extending up into the liquid compartment;

Figure 3 is a plan view of the glass in Figure 1;

Figure 4 is a bottom view of the glass in Figure 1;

Figure 5 is a side elevational view of the cup for the solid carbon dioxide;

Figure 6 is a side elevational view of the cork plug, and

Figure 7 is a vertical sectional view of the cup and plug assembly.

As shown in the drawing, a serving glass 10 consists of a vertical cylinder subdivided into two compartments 11 and 12 by a bottom partition 13. A handle 14 for the vessel is provided to permit manipulation of the glass.

In order to permit the liquid in the compartment 11 to be kept cooled against the warming influence of ambient temperature, an auxiliary compartment 15 is provided to receive and hold a cooling medium. The compartment 15 is provided by and within a glass receptacle 16 inverted and extended upward into the main compartment 11 of the glass. Access to the auxiliary cooling compartment 15 is available from the bottom of the vessel 10 through the main bottom partition 13, upon which the inverted receptacle 16 is supported.

The bottom partition 13 is provided with an opening 18 through which access may be had to the cooling compartment 15. A plug or cork 19 of the usual truncated cone shape with a tapered external surface is provided of proper size to 50

permit it to be snugly fitted into the opening 18 in the bottom parts of the vessel.

Plug 19 is provided with an axial passage 21 to permit a free passage for the cooling gas from the 5 solid carbon dioxide that is used as the cooling medium.

In order to prevent localization of the cooling effect of the carbon dioxide and in order to ensure a uniform cooling of the wall of the cooling 10 receptacle 16, a cup 22 is supported in position by the plug or cork 19 in spaced relation from the glass surface. The cup 22 consists of the cylindrical body 23 and a lower co-axial extension 24. The body portion 23 is hollowed out at one 15 end to provide a recess or cup compartment 25 for the carbon dioxide to serve as the cooling medium. The portion of the body below the cup compartment 25 is provided with one or more passages 26 extending through the body of the 20 support or sufficiently far into the body to communicate with the longitudinal passage 27 through the lower extension 24.

When the glass vessel is to be used to serve a 25 liquid drink, a piece of solid carbon dioxide is placed in the recess of the cup 22 that is already associated with a cork as shown in Figure 7 and the entire assembled unit is inserted into the opening 18 in the bottom 13 of the vessel. The liquid to be served is then placed in the usual 30 compartment 11. As the solid carbon dioxide becomes heated, its gas moves up over the top edge 28 of the body cup and moves down along the inner surface of the auxiliary cooling chamber vessel 16 on its way to the exit passages 26 35 and 27 at the bottom of the support and through the support 19.

In order that the gas so formed may not be trapped within the bottom of the drinking vessel, the lower edge of the vessel 29 is provided 40 with one or more notches 31 through which the carbon dioxide gas may readily pass.

By means of the construction illustrated, the cork and support for the carbon dioxide may be readily inserted in position for use or removed to 45 permit washing of the vessel. With the construction of the cup as shown and the combined relation with the auxiliary compartment, the entire compartment wall is cooled thereby ensuring uniform cooling of the liquid within the glass vessel. The provision of the pressure relieving 50 notches at the bottom edge of the vessel prevents building up of pressure by the carbon dioxide gas, that might unduly stress the elements of the vessel.

55 The plug or cork 19 is preferably made of rubber so that it may be easily washed and handled, while at the same time providing a heat-insulating support for the cup element 22, which may be of light metal or of molded material.

60 A cold drink, if served when the ambient temperature is considerably higher, tends quickly to become warm. In the case of beer, the rise in temperature affects its flavor. When served in a glass of the type described, with a small pellet 65 of dry ice in the cooling compartment, the cold temperature of the liquid in the main compartment may be held at its initial temperature for an extended time interval.

67 My invention is not limited to the specific details of construction that are illustrated nor is the invention limited in its application to use 70 with a vessel of the kind described, since the details may be variously modified and the invention may be variously applied to vessels of the 75 different kinds used as drinking vessels or as

dispensers' vessels, without departing from the spirit and scope of the invention as set forth in the appended claims.

I claim as my invention:

1. A liquid drinking or serving vessel comprising a main shell having a main compartment to receive and hold a liquid, and an auxiliary shell mounted on the main shell and disposed to extend into the main shell and to serve as a partition between the main compartment and the space or 10 compartment in the auxiliary shell; and means serving as a support for a dry ice cooling medium extending into the auxiliary compartment to cause the cooling medium to engage and pass over the inner surface of the partition as the gaseous 15 cooling medium passes out of the cooling chamber.

2. A liquid drinking or serving vessel, comprising a cylindrical glass shell having a main body compartment and an auxiliary cooling compartment separated from the main compartment by a partition extending into the main compartment, and a cup-shaped support to hold a piece of dry ice in position to cause the gaseous carbon-dioxide to pass over the surface of the partition as the gas passes out of the cooling compartment.

3. A drinking or serving vessel comprising a container having a main compartment for the liquid, a false bottom to support the main compartment above the lowermost plane of the vessel, and an auxiliary vessel extending into the main compartment to constitute and provide a cooling partition between the main compartment and the space in the auxiliary vessel, and means in the auxiliary vessel to support a piece of dry ice as a cooling medium in an elevated position in the auxiliary vessel to compel the gaseous carbon-dioxide to engage the partition wall of the auxiliary chamber in its passage to 40 the space of the false bottom and thence to the outer air.

4. A drinking glass consisting of a cylindrical shell subdivided to include a main compartment and a false bottom partition elevated above the 45 lowest edge of the glass to provide a space below the bottom partition, an auxiliary vessel supported on the false bottom partition and extending upward into the main compartment but closed to said compartment and open to the space below, 50 a support for a body of dry ice and concentrically spaced from the wall of the auxiliary vessel by a narrow space to compel the carbon-dioxide gas to engage and sweep the inner surface of the vessel on its passage out of the vessel, the support 55 having an opening at its lower end to permit the gas to pass through to the space below, and openings in the lower portion of the cylindrical shell to permit the gas to continue on its passage to the outer air.

5. A drinking glass consisting of a vessel subdivided into a main compartment for liquid, an auxiliary compartment separated therefrom by a partition extending into the main compartment, and a false bottom compartment below 65 the other two compartments, and a support for a cooling medium in the auxiliary compartment and having a passageway communicating with the auxiliary and the false compartments to permit the cooling medium to pass from the auxiliary compartment in a path requiring the cooling medium to sweep the surface of the partition.

6. A drinking glass consisting of a vessel subdivided into a main compartment for liquid, an auxiliary compartment separated therefrom by 70

a partition, and a false bottom compartment below the other two compartments, and a support for a cooling medium in the auxiliary compartment and having a passageway communicating with the auxiliary and the false compartments to permit the cooling medium to pass from the auxiliary compartment, and a passage through the wall of the vessel from the false compartment to the outer air to permit the cooling medium to pass therethrough.

7. A drinking vessel subdivided into a main

compartment for a liquid, an auxiliary compartment surrounded by the liquid and separated therefrom by a partition extending into the main compartment, and means for supporting a cooling medium, such as dry ice, in the auxiliary compartment, to keep the liquid cool, said means being disposed to permit the gas from the dry ice to pass out of the auxiliary compartment, and to compel the gas to sweep the partition for maximum cooling effect.

JACK H. ROSEN.
